CLAIM

The ornamental design for a measuring container, as shown and described.

DESCRIPTION

FIG. 1 is a left side perspective view of a measuring container shown in an open position, showing the new design;

FIG. 2 is a top plan view thereof; and,

FIG. 3 is a right side elevational view of the measuring container shown in a closed position thereof.

The broken lines shown in FIGS. 1-3 represent portions of the measuring container that form no part of the claimed design.
